UNITED STATES PATENT OFFICE

139,611

DESIGN FOR A PIPE GAUGE OR SIMILAR ARTICLE

Julius E. Levin, Chicago, Ill.

Application August 19, 1944, Serial No. 114,942

Term of patent 14 years

(Cl. D52—1)

To all whom it may concern:

Be it known that I, Julius E. Levin, a citizen of the United States and a resident of the city of Chicago, in the county of Cook and State of Illinois, have invented a new, original, and ornamental Design for a Pipe Gauge or Similar Article, of which the following is a specification, reference being had to the accompanying drawing, forming a part thereof.

On the drawing:

Figure 1 is a plan view of a pipe gauge showing my new design;

Figure 2 is an edge view thereof taken from the top of Figure 1; and

Figure 3 is a view similar to Figure 1, showing the parts of the gauge in a measuring position.

I claim:

The ornamental design for a pipe gauge or similar article, as shown and described.

JULIUS E. LEVIN.
